UNITED STATES PATENT OFFICE.

LEWIS A. BEDARD, OF BOSTON, MASSACHUSETTS.

BUFFER FOR DOORS.

1,071,134.

Specification of Letters Patent.

Patented Aug. 26, 1913.

Application filed December 16, 1912. Serial No. 736,983.

To all whom it may concern:

Be it known that I, LEWIS A. BEDARD, a citizen of the United States of America, and a resident of Boston, in the county of Suffolk and State of Massachusetts, have invented certain new and useful Improvements in Buffers for Doors, of which the following is a specification.

This invention relates to cushioning devices to prevent noise resulting from the closing of doors, and has particular reference to that type of such devices known as buffers, one device of such nature being shown in U. S. Patent No. 1,022,651, granted 15 to me April 9, 1912.

The object of the present invention is to provide a device of the character illustrated in said patent but which will be simpler and easier to make and easier to apply.

20 To these ends the invention consists in the improvements which I shall now proceed to describe and claim.

Of the accompanying drawings: Figure 1 is a perspective view of a portion of an automobile body and door jamb having one of my improved devices applied thereto. Fig. 2 is an elevation partly broken out or in section of line 2-2 of Fig. 1. Fig. 3 represents a section on line 3-3 of Fig. 2. Fig. 4 represents a section on line 4-4 of Fig. 1. Fig. 5 is a view similar to Fig. 4 but showing the door also, the door being closed and the buffer cushion or sliding head pushed into the casing. Fig. 6 is a perspective view of the casing and its attaching flanges.

The same references indicate the same parts in all the figures.

A portion of the body of a vehicle such as an automobile is shown at 10, said body having a jamb 11 for the door 12 (Fig. 5). The face of the jamb 11 is narrow, frequently narrower than shown in the drawings and it is recessed or rabbeted to receive the casing 13 of the device, said casing being laterally narrow and vertically elongated. The casing 13 is formed or provided with flanges 14 having suitable holes for screws to secure the device in place. The casing 13 is plain in the sense that it has no ribs and consequently it may be economically manufactured, as by casting. Slidably mounted within the casing 13 is a buffer head 15 which is preferably of such material

as vulcanized fiber. Mounted within the 55 casing and between the bottom thereof and the inner face of the head 15 are two coiled springs 16 which normally hold the buffer head in substantially the projected position indicated in Figs. 1, 2 and 4. To prevent 60 the head from being ejected from the casing, and also to aid in guiding it in its sliding movements in said casing, I provide a guide loop 17 which embraces a cross pin 18 which extends transversely of the casing as shown 65 in Figs. 2, 3, 4 and 5. The guide loop 17 preferably consists of a flat strip of metal bent to elongated U form and having its ends bent outwardly as indicated at 19 in Fig. 2. These bent ends 19 serve to anchor 70 the guide loop in the head 15, it being understood that when the said head 15 is made of vulcanized fiber, it may be molded relatively to the guide loop, as shown in Fig. 2.

In practice the face of the door jamb is 75 mortised or recessed for the device, the face which includes the flanges 14 being polished or plated. The buffer presents a vertically elongated cushion or head of such area that, although restricted as to width, no indenting 80 or cracking of the door slamming against it can occur. Such vertical elongation results in less noise of contact than if a small round buffer possessing the necessary resistance were employed. The ends of the springs 85 16 may be embedded or seated in shallow sockets formed in the rear face of the head 15 so as to retain the springs in their proper relative positions where they cannot interfere with the rearward movement of the 90 guide loop 17 when the head is pushed in as shown in Fig. 5. Said springs are of course held separate from the guide loop so that no noise or squeaking can result from contact with the guide loop of said springs. 95 Owing to the fact that the guide loop is made of a flat strip of metal the width of which is substantially equal to the interior laterally of the casing, as clearly shown in Fig. 5, the edges of said guide loop will be guided 100 by the inner faces of the said members of the casing 13 so as to prevent any lateral rocking or tilting of the elongated head as it slides in the casing.

I claim:

1. A buffer for a door jamb comprising a casing having a transverse guide pin, and a spring-projected buffer head slidably

mounted in said casing and having a rearwardly extended loop embracing said guide pin.

2. A buffer for a door jamb comprising a laterally narrow and vertically elongated casing having flanges whereby the casing may be secured in place, said casing having a transverse guide pin, a buffer head slidably mounted in said casing and having a 10 rearwardly extending flat loop embracing

said guide pin, and springs on opposite sides of the guide pin and loop confined between said head and the bottom of the casing.

In testimony whereof I have affixed my signature, in presence of two witnesses.

LEWIS A. BEDARD.
